(57) **CLAIM**

The ornamental design for a golf training aid, as shown and described.

DESCRIPTION

FIG. 1 illustrates a top perspective view of the golf training aid.

FIG. 2 illustrates a front view of the golf training aid shown in FIG. 1.

FIG. 3 illustrates a back view of the golf training aid shown in FIG. 1.

FIG. 4 illustrates a side view of the golf training aid shown in FIG. 1.

FIG. 5 illustrates another side view of the golf training aid shown in FIG. 1.

FIG. 6 illustrates a top view of the golf training aid shown in FIG. 1.

FIG. 7 illustrates a bottom view of the golf training aid shown in FIG. 1.

FIG. 8 illustrates a bottom perspective view of the golf training aid shown in FIG. 1.

FIG. 9 illustrates an elevational view of the golf training aid inserted into the broken line showing of the ground as well as the ball being shown in an alternate position.

FIG. 10 illustrates a top perspective view of a second embodiment of the golf training aid.

FIG. 11 illustrates a front view of the golf training aid shown in FIG. 10.

FIG. 12 illustrates a back view of the golf training aid shown in FIG. 10.

FIG. 13 illustrates a side view of the golf training aid shown in FIG. 10.

FIG. 14 illustrates another side view of the golf training aid shown in FIG. 10.

FIG. 15 illustrates a top view of the golf training aid shown in FIG. 10.

FIG. 16 illustrates a bottom view of the golf training aid shown in FIG. 10.

FIG. 17 illustrates a bottom perspective view of the golf training aid shown in FIG. 10.

FIG. 18 illustrates an elevational view of the golf training aid inserted into the broken line showing of the ground as well as the ball being shown in an alternate position; and, FIG. 19 illustrates a top perspective view of the coupling component of the golf training aid, shown separately for clarity.

The broken lines disclosed on the drawings represent portions of the golf training aid that form no part of the claimed design.
